HANDLE FOR A SCREWDRIVER

Laird Fortune Covey, Easton, Conn. (% The Stanley Works, 195 Lake St., New Britain, Conn. 06050)

Filed Aug. 6, 1973, Ser. No. 386,004

Term of patent 14 years

Int. Cl. D8—04

U.S. Cl. D8—83

FIG. 1

FIG. 2

FIG. 3

FIG. 1 is a side elevational view of a handle for a screwdriver showing my new design;

FIG. 2 is a bottom plan view thereof; and

FIG. 3 is a top plan view thereof.

I claim:

The ornamental design for a handle for a screwdriver, as shown.
